(57) **CLAIM**

The ornamental design for an illumination device, as shown and described.

DESCRIPTION

FIG. 1 is a perspective view of an illumination device showing our new design;

FIG. 2 is a top view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is a second perspective view thereof.

The broken line showing of various features of the illumination device depicts environmental subject matter only and forms no part of the claimed design.
